CLAIM

The ornamental design for a pipe end preparation tool, as shown.

DESCRIPTION

FIG. 1 is a front elevational view of a pipe end preparation tool, showing my new design;

FIG. 2 is an elevational view of one side, the opposite side being substantially a mirror image thereof;

FIG. 3 is a rear elevational view;

FIG. 4 is a bottom plan view; and,

FIG. 5 is a top plan view.
